UNITED STATES PATENT OFFICE

2,605,683

TROWELING MACHINE

Harold S. Boulton, Evanston, Ill., assignor, by direct and mesne assignments, to Master Vibrator Company, Dayton, Ohio, a corporation of Ohio

Application January 11, 1947, Serial No. 721,574

9 Claims. (Cl. 94—45)

1

This invention pertains to surfacing implements, and more particularly to a rotary power driven apparatus having progressive circular wiping engagement over the surface upon which it operates.

While, for illustrative purpose, the invention is herein shown and described as embodied in a concrete troweling machine or float for finishing concrete surfaces and hard or mastic toppings for concrete sub bases but is obviously not limited thereto. By substitution of suitable work engaging elements, the present rotary power driven apparatus may be utilized for grinding, cleaning or scrubbing operations, or when equipped with abrasive work faces may be employed to smooth tessellated and terrazzo floors and when equipped with felt or other soft friction applicators, it may be used for waxing and polishing floor surfaces.

The concrete finishing embodiment of the rotary power driven apparatus forming the subject matter hereof, involves radial sweeps which are easily and quickly convertible for floating and for finishing a concrete surface or interchanged for other sweeps adapted to other operations.

The object of the invention is to improve the construction as well as the means and mode of operation of rotary surface treating apparatus, whereby it may not only be economically constructed, but will be more efficient in use, automatic in operation, uniform in action, having a minimum number of working parts, and be unlikely to get out of repair.

A further and important object of the invention is to minimize the time and the tiresome labor required for hand troweling and surface finishing concrete floors and roadways, and thereby minimizing the cost of such construction.

A further object of the invention is to provide working surfaces on opposite sides of reversible sweeps adapted to performance of surfacing results of different character.

A further object of the invention is to produce surface wiping action of one of the working surfaces different from that of the other surface, suitable for finishing and completion of operations previously performed by such other working surface.

A further object of the invention is to provide a working surface on each sweep substantially equal to the total area of the individual sweeps.

A further object of the invention is to provide a power driven rotary surface treating apparatus embodying the advantageous structural features, the inherent meritorious characteristics and mode of operation herein set forth, or their equivalents.

2

With the above primary and other incidental objects in view as will more fully appear in the specification, the invention intended to be protected by Letters Patent consists of the features of construction, the parts and combinations thereof, and the mode of operation as hereinafter described or illustrated in the accompanying drawings, or their equivalents.

In the accompanying drawings, wherein is shown the preferred, but obviously not necessarily the only form of embodiment of the invention,

Fig. 1 is a perspective view of a power driven rotary concrete floating and finishing machine embodying the present invention.

Fig. 2 is a side elevation of an assembled sweep disconnected from the apparatus.

Fig. 3 is an end view thereof.

Fig. 4 is a top plan view of the sweeps showing the finishing blades disposed in parallel offset positions relative to the radii of their common axis about which they oscillate, and tangential to a circle concentric thereto.

Fig. 5 is a similar top plan view of the sweeps showing the finishing blades thereof likewise disposed tangentially to a circle concentric with the axis of rotation but extending in transverse angular relation to the radii thereof.

Figs. 6 and 7 are bottom plan views of the detached finishing blades when arranged as shown in Figs. 4 and 5 respectively.

Fig. 8 is an enlarged perspective view of the end of an assembled sweep and guard ring.

Like parts are indicated by similar characters of reference throughout the several views.

The present disclosure is an improvement and further development of that shown and described in pending application Serial No. 681,711 of Harold E. McCrery now Patent No. 2,594,331 of which pertinent portions are herein shown and described for illustrative purposes, but which, per se, form no part of the instant invention, which is directed to the disposition of the finishing blades of the sweeps.

Referring to the accompanying drawings, the rotary surfacing machine in Fig. 1 comprises a rotary base 1 from which radiate a plurality of reversible sweeps 2—2, surrounded by a guard ring 3 upon which the outer ends of the sweeps 2 are pivoted. Located in axial relation above the revoluble base 1 is a gear housing 4 surmounted by a driving motor 5. The motor shown in Fig. 1 is a conventional explosive engine or hydrocarbon motor. An electric motor may be substituted for the explosive engine 5. A driving pulley 6 of the motor, of whatever type,

is connected by V belt 7 with a driven pulley 8 of the gear driving mechanism within the housing 4. A handle 9 extends upwardly and radially from the housing 4 for controlling and guiding the machine. Manually operated control devices 10 mounted on the handle 9 within easy reach of the operator, are connected through the handle shaft with the actuating motor 5.

The power transmission, driving and adjusting features of the instant disclosure are substantially those of the copending application aforementioned, to which reference is made.

Obviously scrub brushes can be substituted for the troweling plates 19-20, thereby converting the apparatus into a power operated scrubbing machine. Likewise abrasive faced elements may be utilized in lieu of the troweling plates, for smoothing a surface operated upon, and by employing friction faces on the sweeps the apparatus may be used for waxing and polishing the surface operated upon.

The instant sweeps 2 comprise vertically disposed Z-bars 11 having oppositely projecting top and bottom marginal flanges 12 and 13 to the inner ends of which bars are welded short rectangular bars 14 which extend beyond the angle bars as cylindrical trunnion shafts 15 aligned with the center line of the Z-bars 11. Welded to the rectangular bars 14 are oppositely extending rock arms 16 which serve to rotatively adjust the sweeps about their longitudinal axes by engagement with the oscillatory spider 25. Movement of the spider 25 to rock the sweeps about their longitudinal axes is controlled by hand wheel 26. At the opposite ends of the angle bars 11 there are welded thereto in axial alignment with the trunnions 15 rectangular collars 17 within which engage trunnion studs 18 welded to the surrounding guard ring 3.

The web portions of the angle bars 11 are disposed substantially coincident with the radii of the axis about which the sweeps rotate. Attached to the bottom flange of the sweep bars 11 are surface plates or floats 19 which are comparatively wide and perform the initial concrete surfacing operations of distributing and leveling the concrete material. The top flanges 12 of the sweep bars 11 are somewhat wider than the bottom flanges 13, thus enabling the finishing or secondary plates or shoes 20 to be laterally offset preferably rearwardly in their direction of rotation, relative to the primary or float blades 19 and with their axes tangential to a circle a , concentric to the common axis of rotation of the sweeps. As shown in Fig. 4 the finishing blades 20 may be offset with their axes parallel to the axes of the companion primary or float blades 19. However without changing the tangential relation of the axes of the finishing blades to the concentric circle a , the blades may be inclined transversely of the companion primary float blades 19 and hence in angular relation with the radii of the several sweeps 2 as shown in Fig. 5.

To connect the blades in either position, each blade 20 is provided on its under surface with a longitudinal channel 21. A corresponding bar 22 is attached to the flange 12 of the sweep bars 11 by bolts 23. Such bars 22 fit within the channels 21 of the blades 20 and are secured thereto by transverse bolts 24 extending through the side flanges of the channels 21, and through the interposed bars 22. If the blades 20 are to be merely laterally offset in parallel relation with radii of the common axis, the channels 21 are disposed in parallel relation with the margins of 75

the blades 20. If to the contrary the blades are to be disposed in transverse angular relation to the radii and to the companion float blades 19, the channels 21 are welded to the under sides of the blades 20 in a diagonal direction. In either event the bars 22 remain in parallel relation to the sweep bars 11 and fit within the channels 21 whether in parallel or diagonal relation with the blades 20, thus determining the positions of the blades, either parallel or diagonal relative to the sweeps and the radii of the common axis.

The float blades 19 are similarly attached by channels welded to the blades and straddling bars 22 bolted to the sweeps. The float blades 15 are usually disposed with their axis coincident with the radii of the apparatus.

However the float blades may be disposed in transverse angular relation to the radii by similarly diagonally arranging the attachment channels 21. Such diagonal or offset arrangement of either the finishing blades 20 or floating blades 19 affords a "draw cut" wiping action which materially improves the smoothing result of the travel of the blades over the surface operated upon.

The present offset or angular arrangement of the blades 19 or 20 affords a greatly increased working surface on each of the blades. Heretofore, the centrally disposed blades when tilted about the axis of the trunnion shafts 15 presented but a very small area in contact with the surface being treated. By offsetting the axis of the present blades in parallel relation with the axis of the trunnion shafts 15, a greatly increased area is presented in contact with the work surface. When tilted, substantially the entire area of the blades 20 are in working contact with the surface being treated, resulting in increased life of the blades, and more efficient operation of the machine. When blades, centrally disposed relative to the axis of the trunnions, are tilted, approximately one half of the working surface of the blade is raised above the work plane, whereas with the laterally offset blades of the present machine, substantially the entire blade remains below the work plane, even when tilted.

The herein disclosed and described method of assembly of the blades 19-20 to the angle bars 11 forms no part of the present invention, but is shown merely for illustrative purposes and is more fully described and claimed in the copending companion application of Harold E. McCrery, Serial No. 735,627 filed March 19, 1947.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A power driven rotary surface treating ma-

chine, wherein a plurality of relatively angularly disposed sweeps are mounted for unison rotation about a common axis, characterized by a second plurality of sweeps disposed in relatively angular relation different from that of the first plurality of sweeps for rotation in unison therewith in a perpendicularly spaced parallel plane of rotation, reversible supporting means interconnecting sweeps of each plurality in pairs, by reversal of which the sweeps are alternately usable in different angular relations to their paths of rotation over the surface to be treated, a mounting trunnion on the inner ends of said supporting means, and a common mounting for the plurality of sweeps in which said trunnions are rotatably received.

2. A power driven rotary surface treating machine wherein a plurality of sweeps are rotatively actuated about a common axis including a pair of perpendicularly spaced working surfaces on each sweep, disposed in parallel planes of rotation in different angular relation to their direction of travel, a common mounting for the sweeps relative to which the sweeps are reversible to optionally present either of the spaced working surfaces in engagement with the surface operated upon, trunnions on said sweeps rotatably received in said common mounting, and driving means for actuating the sweeps with either of the working faces in operative position, the construction and arrangement being such that the respective working surfaces of each sweep will engage the surface operated upon in a different angular relation to its path of travel thereover with different resulting action thereon.

3. A power driven rotary surface treating machine wherein a plurality of sweeps are rotatively actuated about a common axis including a pair of perpendicularly spaced working surfaces on each sweep, one of which is laterally offset in parallel relation to that of the other in their respective planes of rotation, reversible supporting means interconnecting sweeps of each pair, and means rotatably mounting the sweep supporting means in the machine for alternative use of said working surfaces.

4. A power driven rotary surface treating machine, wherein a plurality of radially disposed sweeps are collectively rotatable about a common axis and are reversibly mounted on a central supporting member characterized by a plurality of auxiliary sweeps disposed in angularly inclined relation with the radially disposed sweeps in a vertically spaced parallel plane of rotation for unison rotation with the radially disposed sweeps for use alternately therewith upon reversal of the sweeps.

5. A power driven rotary surface treating machine, wherein a plurality of radially disposed sweeps are collectively rotatable about a common axis and reversibly mounted on a central supporting member characterized by a plurality of auxiliary sweeps interconnected to the first said sweeps and rearwardly offset relatively to the di-

rection of rotation of the radially disposed sweeps for unison rotation in a parallel plane for alternate use therewith upon reversal of the sweeps.

5. A power driven rotary surface treating machine, wherein a plurality of radially disposed sweeps are collectively rotatable about a common axis and reversibly mounted on a central supporting member characterized by a plurality of auxiliary sweeps interconnected to the first said sweeps and extending parallel with, but laterally offset relative to the radii of the radially disposed sweeps in a vertically spaced parallel plane of rotation, for alternate use upon reversal of the sweeps.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

6. A power driven rotary surface treating machine, wherein a plurality of radially disposed sweeps are collectively rotatable about a common axis including a central supporting member, means rotatably mounting each of the sweeps on said supporting member, and a pair of working blades on each said sweep in vertically spaced relation to be brought alternatively into cooperative relation with the work by rotation of the sweep about its axis, corresponding blades of each pair being disposed with their axes in non-coincident vertical relation with respect to the other blade of the pair.

7. A power driven rotary surface treating machine, wherein a plurality of divergently disposed sweeps are collectively rotatable about a common axis including a central supporting member, means rotatably mounting each sweep on said supporting member, and a pair of working blades on each said sweep in vertically spaced relation to be brought alternatively into cooperative relation with the work by rotation of the sweep about its axis, corresponding blades of each pair being disposed with their axes in non-coincident vertical relation with respect to the other blade of the pair.

8. A power driven rotary surface treating machine, wherein a plurality of divergently disposed sweeps are collectively revoluble about a common axis, including a central support, means rotatably mounting each sweep thereon for rotation about their individual axes, an alternatively usable blade mounted on each of said sweeps with its longitudinal axis in tangential relation to a circle concentric with said common axis, and an offset portion on each of said sweeps to which said alternative blade is attached along its longitudinal axis.

9. A power driven rotary surface treating machine, wherein a plurality of divergently disposed sweeps are collectively revoluble about a common axis, including a central support, means rotatably mounting each sweep thereon for rotation about their individual axes, a blade supporting portion above and below the longitudinal axis of each of said sweeps, one of said portions being in substantially the same radial plane as said sweep and the other portion being laterally offset with respect to such plane, and blades attached along their respective longitudinal axes to said supporting portions.

HAROLD S. BOULTON.
